UNITED STATES PATENT OFFICE.

REINHART K. WHITMAN, OF ALLIANCE, OHIO.

CAR-TRUCK.

No. 825,265.

Specification of Letters Patent.

Patented July 3, 1906.

Application filed August 17, 1905. Serial No. 274,574.

To all whom it may concern:

Be it known that I, REINHART K. WHITMAN, a citizen of the United States, residing at Alliance, in the county of Stark and State 5 of Ohio, have invented certain new and useful Improvements in Car-Trucks; and I do declare the following to be a full, clear, and exact description of the invention, such as will enable others skilled in the art to which 10 it appertains to make and use the same.

This invention relates to car-trucks, and particularly freight-car trucks.

The object of the invention is to provide a truck having improved spring-seat bearings 15 for the truck-bolster.

A further object is to provide an improved bearing between the car and truck bolster, whereby the lubricating-oil and grease will be retained and distributed to the bearings 20 as needed.

With the above and other objects in view the invention consists of certain novel features of construction, combination, and arrangement of parts, as will be hereinafter described and claimed.

In the accompanying drawings, Figure 1 is a side view of a freight-car truck constructed in accordance with the invention. Fig. 2 is a central longitudinal vertical sectional view of the same. Fig. 3 is a transverse vertical sectional view thereof. Fig. 4 is a perspective view of the truck-bolster. Fig. 5 is an inverted perspective view of the car-bolster. Fig. 6 is a side view, partly in 35 section, of one set of the bolster-springs, showing the same arranged in pairs and connected by a double cap-plate. Fig. 7 is a perspective view of a cap-plate used in a single arrangement of the springs, and Fig. 8 is a 40 plan view of a cap-plate used in a group of four springs mounted together.

Referring more particularly to the drawings, 1 denotes the side or truss frames, in which is arranged in the usual manner journal-boxes 2. In the journal-boxes 2 are mounted the ends of the axles 3, on which are arranged the car-wheels 4. The side or truss frames 1 are connected together midway between their ends by means of a channelled cross-bar 5. In the side or truss frames 1 are formed recesses, in which the ends of the channelled cross-bar 5 are adapted to rest. In the ends of the cross-bar 5 are formed bearing recesses or seats 6, said recesses being here shown as semicylindrical in shape, and in the same are adapted to rest

semicylindrical bearing-lugs 7, formed on the under side of a lower spring cap-plate 8, on the upper side of which is formed upwardly-projecting hollow studs 9. The studs 9 are 60 adapted to be engaged by the lower ends of coil-springs 10, the upper ends of which engage similar studs 12, formed on the lower side of an upper cap-plate 13. On the upper side of the cap-plate 13 are formed semicylindrical lugs 14, which are adapted to engage similarly-formed seats or recesses 15, formed in the under side of the ends of the truck-bolster 16, said end being adapted to project into the seats or recesses 6 formed in the 70 truss-frames, whereby said truck-bolster 16 is yieldably supported and guided on the truss or side frames 1. The ends of the truck-bolster are adapted to project slightly beyond the sides of the truss-frames, said 75 ends being provided with laterally-projecting flanges which slidably engage the outer side of the truss-frame, as shown.

There are preferably employed in connection with the truck-bolster 4 four of the supporting-springs 10. These springs are arranged in any suitable manner and are held in place by means of the upper and lower cap-plates 8 and 13, said springs being here shown as arranged and connected by said 80 plates in pairs, the plates in this instance being provided with semicylindrical bearing-lugs to engage bearing-recesses in the ends of the channelled bar and truck-bolster, as hereinbefore described. If desired, however, the 85 springs may be arranged in single form and provided with individual cap-plates, such as are shown in detail in Fig. 7 of the drawings, or the springs may be arranged in groups of four and all connected by single upper and 90 lower cap-plates, such as shown in Fig. 8 of the drawings. The cap-plates, as shown in 95 Figs. 7 and 8, are provided with centrally-disposed hemispherical-shaped bearing-lugs which engage similarly-shaped recesses 100 formed in the end of the channelled cross-bar and the truck-bolster, whereby a loose rocking motion of said bolster is permitted. The springs 10 are preferably double springs, one set being arranged within the other, as 105 shown, the inner set engaging the studs 9 and 12 on the upper and lower cap-plates. The studs 9 and 12 are of hollow construction, and in the lower stud is fixedly mounted an upwardly-projecting guide pin or bolt 17, which 110 is adapted to slidably engage the upper tubular stud, as shown, thereby guiding the upper

cap-plate in its downward movement against the tension of the springs 10.

The ends of the truck-bolster are held in place in the seats 6 of the truck-frames by means of removable caps 18, as shown. On the upper side of the truck-bolster, midway between the ends of the same, is formed an upwardly-projecting cylindrical stud 19, around which is formed an upwardly-projecting annular flange 20. The inner wall of the flange 20 is curved inwardly and downwardly to meet the outwardly-curved wall of the stud 19, thereby forming a concave annular channel around the stud 19. In said curved walls of the flange 20 and stud 19 is formed a series of radially-disposed grooves or channels 21, which are adapted to retain grease or lubricating material.

Adapted to be secured to the under side of the car-body immediately above the truck-bolster is a car-holster 22, said bolster being provided midway between its ends with a downwardly-projecting annular flange 23. The inner and outer wall of said flange is slightly tapered and convex, said flange being thus adapted to fit within the annular groove formed by the stud 19 and flange 20 on the truck-bolster, thus providing a strong pivotal connection between said bolsters. In the walls of the flange 23 is formed a series of grooves or channels 24, which are also adapted to retain lubricating material. By providing the grease-holding grooves or channels 21 and 24 a considerable amount of lubricating material may be stored therein and will be automatically removed therefrom to supply the bearings as needed. On the upper side of the truck-bolster, adjacent to the opposite ends of the same, are journaled side bearing-rollers 25, which are adapted to be engaged by depending bearing plates of bars 26, arranged on the under side of the car-bolster.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. A railway-car truck comprising side truss-frames, a centrally-disposed cross-bar connecting said truss-frames, a truck-bolster, spring-seats formed in cross-bar and bol-

ster, spherical bearing-recesses formed in the bottom of said spring-seats, supporting-springs arranged in said seats, upper and lower cap-plates arranged on said springs, rounded lugs formed on said lower cap-plates to engage said bearing-recesses, said truck-bolster having formed in its under side near its ends a bearing-recess, spherical lugs formed on said upper spring cap-plate to engage said bearing-recess, means to hold said springs in place between said cap-plates, and a car-bolster pivotally mounted on said truck-bolster, substantially as described.

2. A railway-car truck, comprising side truss-frames, a centrally-disposed cross-bar connecting said truss-frames, a truck-bolster, spring-seats formed in the cross-bar and bolster, the ends of said bolster slidably engaging said spring-seats, said seats and inner ends of the bolster having formed therein oppositely-disposed bearing-recesses, sets of double springs arranged in said seats, cap-plates arranged on the upper and lower ends of said springs, inwardly-extending tubular projections formed on the inner sides of said plates, a guide pin or bolt secured in the socket projections of said lower plates and adapted to slidably engage the opposite socket sections on said upper plates, lugs formed on said cap-plates to engage bearing-recesses in said spring-seats and bolster ends, and a car-bolster pivotally mounted on said truck-bolster, substantially as described.

3. A railway-car truck comprising side truss-frames, a centrally-disposed channelled cross-bar connecting said truss-frames, said cross-bar having spherical recesses in the ends thereof, cap-plates provided with spherical lugs to engage said recesses, springs seated in said cap-plates, a truck-bolster, supported at its ends on said springs, caps to hold said ends of the truck-bolster in place, a centrally-disposed bearing-stud formed on said bolster, an annular flange disposed around said stud to form a bearing-socket, a car-bolster, arranged on said truck-bolster, a centrally-disposed, depending annular flange formed on the under side of said car-bolster to engage the bearing-socket formed on said truck-bolster, and means formed in said socket and flange to retain a lubricant, substantially as described.

In testimony whereof I have hereunto set my hand in presence of two subscribing witnesses.

REINHART K. WHITMAN.
